Inventor:
Charles A. Foust,
By his Atty, F. W. Richards

UNITED STATES PATENT OFFICE.

CHARLES A. FOUST, OF GLENDALE, NEW YORK.

SMOOTHING IRON FOR ASPHALT ROADS.

Application filed December 21, 1921. Serial No. 523,946.

To all whom it may concern:

Be it known that I, CHARLES A. FOUST, a citizen of the United States, residing in Glendale, in the county of Queens and State 5 of New York, have invented certain new and useful Improvements in Smoothing Irons for Asphalt Roads, of which the following is a specification.

The present invention relates to smoothing irons, and particularly to heatable smoothing irons for use on heatable plastic material, such as asphalt, in street or road building, and one object is to provide a smoothing iron of the character mentioned 10 which is heated by means appurtenant to, or carried by the smoothing iron, and whereby the time necessary for heating the customary smoothing irons of this description, as by means of a heating furnace, is 15 saved and may be devoted to efficient use of the smoothing iron in its work.

Another object is to provide a smoothing iron of the character mentioned which is heated by electricity.

25 Another object is to provide such a smoothing iron, which permits of rapid work with great saving of time and labor on the part of the operator of the iron and also lessens the number of operators required.

30 These and other objects of a like or kindred nature are accomplished by the invention, one embodiment of which by way of example is described in the following specification and shown in the accompanying drawings in which Figure 1, is a sectional side view on the line 6—6 of Fig. 2, looking in the direction of the arrow.

Figure 2, is a sectional plan view on the line 2—2 of Fig. 1, looking in the direction 40 of the arrow.

Figure 3, is a plan view of the insulator element or filler.

Figure 4, is a detail sectional view on the line 4—4 of Fig. 3, looking in the direction 45 of the arrow.

Figure 5, is a detail sectional side view on the line 5—5 of Fig. 3.

Figure 6, is a detail sectional side view of the assembled device on the line 6—6 of Fig. 50 2, looking in the direction of the arrow.

Similar reference characters denote similar parts throughout the several views.

The invention as shown comprises in its main parts or elements the head A, the handle B, of which only the lower portion ap-

pears, the insulator member C and the resistance coil D.

The head A is preferably of cast iron and has a flat top 10, a nose 11, and a smoothing bottom 12, the head A having a hollow or chambered interior 13 open at its rear or handle end. The bottom 12 is rockered longitudinally, the bottom curving forwardly and upwardly from about the point indicated by α to the nose 11, and curving upwardly from about the point α to the rear end of the bottom for the purpose later stated. Transversely the bottom 12 is flat.

The head A is provided at its rear end at the sides with the extensions 14 and 15, having therein the threaded bolt holes 16 and 17.

The handle B is provided with the yoke-like lower end 18 having the extensions 19 and 20 with holes 21 and 22 therethrough, the threaded ends of the bolts 23 and 24 passing through the holes 21 and 22 and engaging in the screw threaded holes 16 and 17 of the head A for removably securing the handle to the head. Insulating material 25, such as asbestos or transite, is arranged between the ends 14 and 15 of the head A and the extending ends 19 and 20 of the yoke 18 of the handle B.

The yoke-like end 18 and the adjacent portion of the handle A preferably are curved, when viewed from the side, substantially as shown for the purpose later stated.

The insulator member or insulator block C is of refractory dielectric material which is conductive of heat, preferably alundum. The insulator block C when viewed as in Fig. 3, is oblong in shape, substantially conforming in width and height to the interior 13 of the head A for insertion therein, but in length does not occupy all of said interior at the respective ends thereof. The insulator block C comprises the thinner lower portion 26 and the raised portion 27, the raised portion being shorter than the lower portion. The raised portion is provided with the series of parallel longitudinal bores 28, the axes of the bores 28 lying in the central longitudinal plane of the insulator block, and a series of parallel bores 28' extends transversely through the insulator block from the upper to the under side thereof and communicates with the bores 28, the bores 28' constituting means for distributing heat from the insulator member or insulator block C.

to the head A, the bores 28 being intended to receive the resistance coil D.

The space at the forward end of the interior 13 between the forward end of the interior and the forward end of the lower portion 26 of the insulator block C, has arranged therein the insulating block 29 which extends upwardly for the full height of the interior 13 in the vertical line of the forward end of the block C, thereby providing the space or chamber 30, Figs. 5 and 6, in the interior 13. The space at the rearward end of the interior 13 between the rearward end of the lower portion 26 has arranged therein the insulating block 31 which extends upwardly for the full height of the interior 13 in the vertical line of the rearward end of the block C, thereby providing the space or chamber 32 in the interior 13, the sides 33 and 34 of the insulating block 31 being extended to bear against the adjacent faces of the insulating material 25 located between the head A and handle B, for preventing movement of the insulating blocks and insulator block C in the interior 13. The extended sides 33 and 34 of the insulating block 31 thus provide an open space or chamber 35 at the rearward end of the interior 13.

The insulating block 31 has near the sides thereof and extending therethrough the parallel holes 36 and 37, for wires, and has secured therein, between the holes 36 and 37, the binding posts 38 and 39, the heads of which are located in said open space or chamber 35.

The insulating blocks 29 and 31 preferably are of transite.

The resistance coil D is a continuous coil of wire, preferably of nichrome or chromium alloy. The coil D is passed through the series of bores 28 of the insulator block C in a series of reverse curves, the coil passing first in one direction and then in the opposite direction through the bores, the curved ends of the coil being located in the open spaces or chambers 30 and 32, and the wire at the respective ends of the coil being extended through the holes 36 and 37 in the insulating block 31, and secured to the respective binding posts 38 and 39. Suitable wires from a source of electricity are connected to the respective binding posts 38 and 39 for providing an electric current through the coil D, these wires preferably being led through the handle B which is hollow for this purpose. Heat from the coil D is communicated to the insulator block C, which being of refractory dielectric material conductive of heat, the heat is distributed or transmitted to the head A, by the series of bores 28', the temperature being about 1500° F.

It will be noted that the longitudinally curving under surface of the bottom 12 of the head A, in operation, prevents the pil-

ing up and pushing forwardly of the heatable plastic material by the nose of the smoothing iron, the smoothing iron riding over the material and, due to its heat and the flat surface of the bottom 12 transversely, melting the material and smoothing it out. In addition the curve of the bottom from about the point x rearwardly permits the nose of the head A to be tilted upwardly by downward pressure of the operator on the handle B, whereby the rearwardly curving portion provides a spreading smoothing finish for the plastic material.

Having thus described my invention, it should be understood that there may be modifications thereof and variations therein without departing from the spirit of the invention or exceeding the scope of the appended claims.

What I claim and desire to protect by Letters Patent is:—

1. In a smoothing device, the combination of, a heatable head; and a member located within the head comprising heat generating means; said member being provided with a plurality of bores for receiving the heat generating means therein and a plurality of bores cooperating with the heat generating means for distributing heat therefrom to the head.

2. In a smoothing device, the combination of, a heatable head; and a member located within the head and enclosed thereby comprising heat generating means; said member being provided with a plurality of bores for receiving the heat generating means therein and a plurality of bores cooperating with the heat generating means for distributing heat therefrom to the head.

3. In a smoothing device, the combination of, a heatable head; and a member located within the head comprising heat generating means and means cooperating with the heat generating means for distributing heat from the generating means transversely thereof to the head.

4. In a smoothing device, the combination of, a heatable head; and a member located within the head and enclosed thereby comprising heat generating means and means cooperating with the heat generating means for distributing heat from the generating means transversely thereof for heating the head.

5. In a smoothing device, the combination of, a heatable head; and a dielectric member located within the head comprising electric heat generating means; said member being provided with means for operatively receiving said heat generating means therein and means cooperating with said receiving means for distributing heat from the generating means to the head.

6. In a smoothing device, the combination of, a heatable head; and a dielectric

- member located within the head comprising electric heat generating means; said member being provided with means for operatively receiving said heat generating means 5 therein and means cooperating with said receiving means for distributing heat from the generating means transversely thereof to the head.
7. In a device for smoothing heatable plastic material, the combination of, a head; and means for electrically heating the head; said means comprising a member of aluminum disposed within said head.
8. In a device for smoothing heatable plastic material, the combination of, a head; and means for electrically heating the head; said means comprising a member of refractory dielectric material disposed within said head and arranged for distributing 15 heat to the head.
9. In a device for smoothing heatable plastic material, the combination of, a head; and means for electrically heating the head; said means comprising a member of aluminum disposed within said head and arranged for distributing heat to the head.
10. In a device for smoothing heatable plastic material, the combination of, a head; and means for heating the head; said means 20 comprising a member disposed within said head, heat generating means appurtenant to said member, and means for distributing heat to the head from the generating means.
11. In a device for smoothing heatable plastic material, the combination of, a head; and means within the head for heating the head; said means comprising a member disposed within the head provided with bores for disposition of heat generating means 25 30 therein and bores for distributing heat from said generating means to the head.
12. In a device for smoothing heatable plastic material, the combination of, a head; and means within the head for heating the head; said means comprising a member disposed within the head provided with longitudinal bores for disposition of heat generating means therein and transverse bores for distributing heat from said generating 35 40 45 means to the head.
13. In a device for smoothing heatable plastic material, the combination of, a head; and means within the head for heating the head; said means comprising a member disposed within the head provided with longitudinal bores for disposition of heat generating means therein and transverse bores for distributing heat from said generating means to the head, the transverse bores communicating with the longitudinal bores.
14. In a device for smoothing heatable plastic material, the combination of, a head; and means within the head for heating the head; said means comprising a member disposed within the head, heat generating 50 55 60 65 70 75 80 85 90 95 100 105 110 115 120 125 means extending through said member, and means for distributing heat from said generating means to the head.
15. In a device for smoothing heatable plastic material, the combination of, a head; and means for heating the head; said means comprising a member disposed in said head, heat generating means extending through the interior of said head and extending through said member first in one direction and then in the opposite direction, and means for distributing heat from said generating means to the head.
16. In a device for smoothing heatable plastic material, the combination of, a head; and means for heating the head; said means comprising a member disposed in said head provided with longitudinal bores, heat generating means extending through said bores, and means for distributing heat from said generating means to the head.
17. In a device for smoothing heatable plastic material, the combination of, a head; and means for heating the head; said means comprising a member disposed in said head provided with longitudinal bores and transverse bores communicating with the longitudinal bores, and heat generating means disposed in the longitudinal bores.
18. In a device for smoothing heatable plastic material, the combination of, a head; and means for electrically heating the head; said means comprising a member of refractory dielectric material disposed within the head, a resistance coil appurtenant to said member, and means for distributing heat from the resistance coil to said head.
19. In a device for smoothing heatable plastic material, the combination of, a head; and means for electrically heating the head; said means comprising a member of refractory dielectric material disposed within the head, a resistance coil continuously extending through said member, and means for distributing heat from the resistance coil to said head.
20. In a device for smoothing heatable plastic material, the combination of, a head; and means for electrically heating the head; said means comprising a member of refractory dielectric material disposed within the head provided with longitudinal bores and transverse bores communicating with the longitudinal bores, and a resistance coil continuously extending through said longitudinal bores.
21. In a device for smoothing heatable plastic material, the combination of a head; and means for electrically heating the head; said means comprising a member of refractory dielectric material disposed within the head provided with longitudinal bores and transverse bores communicating with the longitudinal bores, there being space in the interior of the head at the ends of said

member, and a continuous resistance coil extending by reverse curves through said space and extending through the longitudinal bores of said member.

5. 22. In a device for smoothing heatable plastic material, the combination of, a head provided with a nose and a smoothing bottom surface and having a hollow interior; means for operating said head; a member 10 of refractory dielectric material arranged in said interior and having longitudinal bores therethrough; a resistance coil extending continuously through said bores first in one direction and then in the opposite direction; and means for supplying electricity to said coil.

23. In a device for smoothing heatable plastic material, the combination of, a head provided with a nose and a smoothing bottom 20 surface and having a hollow interior; means for operating said head; a member of refractory dielectric material arranged in said interior and having therethrough longitudinal bores and transverse bores communicating with the longitudinal bores; insulating means arranged in said interior forwardly of said member and insulating means arranged in said interior rearwardly of said

member; a resistance coil extending continuously through said longitudinal bores 30 first in one direction and then in the opposite direction; and means for supplying electricity to said coil.

24. In a device for smoothing heatable plastic material, the combination of, a head provided with a nose and a smoothing bottom surface rockered longitudinally and flat transversely, the head having a hollow interior; means for operating said head; a member of refractory dielectric material arranged in said interior and having therethrough longitudinal bores and transverse bores communicating with the longitudinal bores; insulating means arranged in said interior forwardly of said member and insulating material arranged in said interior rearwardly of said member; a resistance coil extending continuously through said longitudinal bores first in one direction and then in the opposite direction; and means for supplying electricity to said coil. 40 45 50
